CLAIM

The ornamental design for a lower body garment, as shown and described.

DESCRIPTION

FIG. 1 is a left side, top perspective view of a lower body garment showing my new design.

FIG. 2 is a left-side, bottom perspective view of my new design shown in FIG. 1.

FIG. 3 is a front view of my new design shown in FIG. 1.

FIG. 4 is a rear view of my new design shown in FIG. 1.

FIG. 5 is a right-side view of my new design shown in FIG. 1.

FIG. 6 is a left-side view of my new design shown in FIG. 1.
